UNITED STATES PATENT OFFICE.

NATHAN S. HASELTINE, OF SWISSVALE, PENNSYLVANIA.

AUTOMATIC SAFETY DEVICE FOR CRANES.

No. 889,126.

Specification of Letters Patent.

Patented May 26, 1908.

Application filed August 16, 1907. Serial No. 388,773.

To all whom it may concern:

Be it known that I, NATHAN S. HASELTINE, a citizen of the United States, and residing in the borough of Swissvale, in the county of Allegheny and State of Pennsylvania, have invented or discovered new and useful Improvements in Automatic Safety Devices for Cranes, &c., of which the following is a specification.

10 My invention consists in a new and improved safety switch for electric cranes and similar mechanisms, whose office is to automatically break the power circuit and stop the operation of the mechanism to prevent 15 accident.

The invention is arranged to be operated automatically by the mechanism without the interference of the operator, so that accident from the carelessness of the operator or 20 loss of control of the mechanism is avoided.

In illustrating and describing my invention I have shown it arranged to prevent an overwind of an electric crane but it will be evident that it may also be arranged to prevent 25 too great lowering of the load without altering the cardinal features of the invention.

In the construction shown I have illustrated a convenient method of wiring where- 30 by, when the safety switch has been thrown, further elevation of the load is impossible but the same may be lowered if desired. However, my switch may be arranged as an absolute cut-out so that when operated, the 35 load may be neither raised or lowered until the switch is again set. I provide efficient locking means whereby the switch is maintained in its normal position, permitting the crane to be operated in the usual manner and 40 means whereby, after the switch is unlocked, it is kicked forcibly out of engagement with the contact thus overcoming any slight fusing between switch and contact and assisting the spring which is usually provided to throw 45 out the switch when the locking means is released.

I also show novel construction and arrangement of parts and operative connections to attain the above results which will 50 appear from the following description.

In the accompanying drawings, which are merely illustrative of the practical adaptation of my invention and not intended to limit the scope thereof to the construction shown, Fig- 55 ure 1 is a front elevation of my invention shown operatively connected to the cable drum of a

crane or other mechanism; Fig. 2 is a side elevation of the same looking in the direction of the arrow in Fig. 1, partially in section along the line I—I in said figure; Fig. 3 is a rear elevation of the switch board showing the wire connections; Fig. 4 is a diagrammatic figure illustrating a convenient method of wiring a crane for my invention, while Fig. 5 is a front elevation of a modification of the 60 structure of Fig. 1 wherein the switch is operated by the cable block.

The following is a detailed description of the drawings: 1 is a cable drum whose shaft 2 is operatively connected by any convenient 65 means to a worm shaft 3 journaled in a frame 4 attached to the crane.

5 is a switch board, preferably consisting of a triangular wooden board, also secured to the crane.

6 is a switch lever pivoted to the top of board 5 by stud 7 which passes through said board and to which an electric wire is attached to place said switch in circuit.

8 and 9 are contacts of the ordinary spring 80 design placed at either of the lower corners of board 5, into engagement with either of which contacts the switch 6 may be brought.

10 is an arm keyed to stud 7 so as to be stationary.

11 is a spiral or other spring attached at one end to arm 10 and at its other end to the switch 6 adjacent to its lower end. The point of connection between said spring and said switch is a handle by means of which 85 said switch may be thrown by hand. It is evident that spring 11 will automatically throw and maintain switch 6 in engagement with contact 9 unless said switch is locked in 90 engagement with contact 8 in the manner to 95 be described.

13 is an extension plate secured to board 5 in any convenient manner and to which is pivoted the bell crank lever 14 provided with three arms, 15, 16 and 17. The lower arm 15 is 100 pivoted at its free end to one end of the link 18 whose outer end is pivoted to the upper end of lever 19 which is pivoted intermediate of its ends to ears 20 mounted on frame 4. On worm shaft 3 moves screw block 21 whose 105 upper extremity extends through longitudinal slot 22 in frame 4, thus preventing said block from rotating with the worm and causing it to move lengthwise of said slot. The worm and block are arranged so that in winding up the drum the block moves toward the 110 depending end of lever 19 and in unwinding

the drum the movement of the block is in the other direction. The lever 19 extends downwardly sufficiently to be engaged by said block 21 when the drum has been wound up to a predetermined limit where the drum must be stopped to prevent accident. When the block comes into contact with lever 19, it kicks the lower end thereof toward the right in Fig. 1, thus moving the link 18 longitudinally toward the left, rocking the bell crank lever 14 toward the right on its pivot point. The arm 16 of lever 14 is provided at its outer end with a lateral stud 23 which engages a slight notch in the lower portion of switch 6 thus locking the switch when the lever 14 is in the position shown in Fig. 1. It is evident that the rocking of said lever 14, as above described, will depress the arm 16 and release the switch so that the spring 11 may throw the same out of engagement with contact 8 and into engagement with contact 9. As it frequently happens that the switch refuses to respond to the tension of the spring owing to a slight fusing of metal between the switch and the contact 8, I provide the following means for disengaging the switch from said contact to permit the spring to work effectually.

The upper arm 17 is provided with a lateral roller stud 24 which when the lever 14 is rocked as described, comes into forcible contact with the switch 6 thus kicking it out of engagement with the contact 8. It is thus evident that when the cable drum has been wound up to a predetermined point, beyond which there is danger of an accident, the block 21 throws lever 19, thus rocking lever 14, releasing the locking pin 23, kicking the switch 6 out of engagement with contact 8 and allowing the spring 11 to throw said switch into engagement with contact 9.

In Fig. 4 I have shown a convenient method of wiring for my invention. 25 represents the motor and 26 its field. 27 represents the positive main and 28 the negative main. The controller is represented by points *a*, *b*, *c*, and *d*. The positive main 27 is connected to controller point *d* while the negative main 28 is connected to field 26. The motor 25 is connected by wire 29 to switch 6 and also to point *b* by wire 30. The contact 8 is connected by wire 31 to point *c*, and the contact 9 is connected to point *a* by wire 32 which is also connected to field 26 by wire 33. When the switch 6 is in engagement with contact 8, as shown in full lines in Fig. 4, as is its position in the normal operation of the crane or other mechanism fitted with my invention, by setting the controller so that point *a* is connected with point *b*, and point *c* with point *d* the motor will be driven in one direction, say, in the proper direction to wind up the cable on the drum. If, on the other hand, the points *a* and *c* be connected, and likewise the points *b* and *d*, the motor

will be reversed and the cable unwound. When the points *a* and *b*, and the points *c* and *d* are, respectively connected, as the drum winds up the cable, the screw block 21 will gradually approach the lever 19 until, when the predetermined danger point is reached, the block 21 will force aside said lever 19, unlocking the switch 6 and kicking it out of engagement with contact 8 and throwing it into engagement with contact 9. It is evident that since the former circuit through switch 6, contact 8 and wire 31 is broken, the motor will come to a stop and the winding up of the cable cease. By throwing the controller to reverse the motor so that points *a* and *c*, and points *b* and *d*, are respectively connected, thus unwinding the drum, a circuit is established through main 27, wire 30, motor 25, wire 29, switch 6, contact 9, wire 32, wire 33, field 26 and main 28, thus allowing the motor to operate. It is thus evident that while the load may be lowered, it can not be raised further while the switch 6 is in contact with contact 9. If contact 9 be omitted, it is evident that when switch 6 ceased to engage contact 8, no circuit could be established through the motor and the crane could not be operated until the switch 6 is again set in engagement with contact 8.

After the operation of the switch 6 as above described, the load is lowered, retreating screw block 21 to the left thus allowing the switch 6 to be swung back, by the operator seizing handle 12, into engagement with contact 8 and the bell crank lever to be swung back into its normal position, by means of handle 34 formed thereon for the purpose, locking switch 6 in place by means of pin 23. The crane is now once more in condition to be operated either for elevating or lowering loads.

While I have described the above construction as used to prevent an overwind, by reversing the construction it may be used to prevent a too great lowering of the load. All that would be required would be a reversal of the pitch of the thread in block 21 to permit its approach to lever 19 when the drum is being unwound and such change in the wiring as to break the lowering circuit when the switch 6 is thrown out of contact with contact 8. Or if desired a second switch mechanism may be installed to control the lowering of loads which may be actuated by the block 21 when it approaches its limit of travel to the left of Fig. 1. The construction in all cases would be the same but a slight and self evident change in wiring would be required.

In Fig. 5 I show a modified form of switch actuating mechanism wherein the switch is thrown by the cable block instead of the drum shaft, a method found especially applicable to some types of cranes. Herein 35 is the cable block mounted on cable 36 wound

on drum 1 and 37 is the equalizing sheave mounted on stationary portion 38 of the crane. 39 is a lever pivoted intermediate of its ends to portion 38 and provided at its outer end with weight 40. On the other side of the pivot point a weight 41 is suspended from said lever by means of a chain 42, said weight being heavy enough to overbalance weight 40. A stop 43 is provided to prevent the lever 39 swinging below the horizontal through the influence of weight 41. The weight 41 is provided at its sides with vertical grooves or recesses 44-44 in which travels the cable 36, thus maintaining said weight in alinement with and above the cable block 35. In this case the lever 14 is provided with two arms 16 and 17 similar to those illustrated in Fig. 1 but the third arm, 15, is rearwardly extending and normally rests upon the inner end of lever 39.

As the cable block 35 rises in the operation of elevating the load, it finally reaches the weight 41 and carries the same up with it, thus allowing the weight 40 to draw down the outer end of the lever 39, thus in turn raising the inner end of said lever which operates to raise the outer end of arm 15 of lever 14, releasing locking pin 23 from the switch 6 and kicking said switch over into engagement with contact 9 with the results above described. By arranging the lever 39 to be thrown by the descent of the cable block, this modification may be adapted to arrest the descent of the load as well as the elevation thereof.

Many modifications of the mechanism used to illustrate the practical adaptability of my invention will occur to those skilled in the art but I do not limit myself to the construction shown in the drawings but claim broadly:—

1. In electric cranes and similar mechanisms, a safety switch, means for locking said switch in its closed position, means actuated by the operation of said crane beyond a predetermined point for disengaging said locking means and means also actuated by the operation of said crane beyond a predeter-

mined point for disengaging said switch from the contact.

2. In electric cranes and similar mechanisms, a safety switch, means for locking said switch in its closed position, means actuated by the operation of said crane beyond a predetermined point for disengaging said locking means, means also actuated by the operation of said crane beyond a predetermined point for disengaging said switch from the contact and spring actuated means for throwing said switch out of its closed position.

3. In electric cranes and similar mechanisms, a safety switch, means for locking said switch in its closed position, means actuated by the operation of said crane beyond a predetermined point for disengaging said locking means and a member also actuated by the operation of said crane beyond a predetermined point adapted to kick said switch out of engagement with the contact.

4. In electric cranes and similar mechanisms, a safety switch, means for locking said switch in its closed position, means actuated by the operation of said crane beyond a predetermined point for disengaging said locking means, a member also actuated by the operation of said crane beyond a predetermined point adapted to kick said switch out of engagement with the contact and spring actuated means for throwing said switch out of its closed position.

5. In electric cranes and similar mechanisms, a safety switch, means whereby when said switch is closed said crane may be operated in either direction, means whereby when said switch is open said crane may be operated in but one direction and means whereby the operation of said crane beyond a predetermined point throws said switch.

Signed at Pittsburg, Penna., this 14th day of August, 1907.

NATHAN S. HASELTINE.
